(57) **CLAIM**

The ornamental design for a locking device, as shown and described.

DESCRIPTION

FIG. 1 is a front, perspective view of the bolt portion of a locking device according to the present invention;

FIG. 2 is a rear, perspective view of the bolt portion of the locking device shown in FIG. 1;

FIG. 3 is a front, perspective view of the catch portion of a locking device according to the present invention;

FIG. 4 is a rear, perspective view of the catch portion of the locking device shown in FIG. 3; and,

FIG. 5 is a front perspective view of the locking device of the present invention.

The bolt portion and catch portion of the locking device are shown separately for convenience of illustration.
